(57) **CLAIM**

The ornamental design for an artificial lash extension as shown and described.

DESCRIPTION

FIG. 1 is a perspective view of a first embodiment of an artificial lash extension showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof.

FIG. 8 is a perspective view of a second embodiment of the artificial lash extension showing my new design;

FIG. 9 is a front view thereof;

FIG. 10 is a back view thereof;

FIG. 11 is a left side view thereof;

FIG. 12 is a right side view thereof;

FIG. 13 is a top view thereof; and,

FIG. 14 is a bottom view thereof.

The broken lines in the figures are for the purpose of illustrating portions of the artificial lash extension, which form no part of the claimed design. The broken away symbol in FIGS. 8-14 indicate the appearance of any portions of the article between the break lines forms no part of the claimed design.

1 Claim, 14 Drawing Sheets
